US0D1021145S

(12) **United States Design Patent** (10) **Patent No.:** **US D1,021,145 S**
(45) **Date of Patent:** **** Apr. 2, 2024**

(54) **LIFT GATE**

(71) Applicant: **Leonard Automatics, Inc.**, Denver, NC (US)

(72) Inventors: **Jeffrey N. Frushtick**, Mooresville, NC (US); **Bradley D. Hamrick**, Shelby, NC (US)

(73) Assignee: **Leonard Automatics, Inc.**, Denver, NC (US)

(**) Term: **15 Years**

(21) Appl. No.: **29/825,569**

(22) Filed: **Feb. 2, 2022**

(51) LOC (14) Cl. **25-02**

(52) U.S. Cl.

USPC **D25/48.5**

(58) **Field of Classification Search**

USPC D25/38.1, 39, 43-45, 48.5, 51, 132; D30/108

CPC E04H 17/1447; E04H 17/006; E04H 17/1417; E04H 17/1482; E04H 17/18; E06B 11/02; E06B 2009/002; E06B 11/045
